UNITED STATES PATENT OFFICE

SEDWICK N. WIGHT, OF ROCHESTER, NEW YORK, ASSIGNOR TO GENERAL RAILWAY SIGNAL COMPANY, OF ROCHESTER, NEW YORK

RAILWAY TRAFFIC CONTROLLING SYSTEM

Application filed July 24, 1931. Serial No. 552,884.

This invention relates to detector and time locking for switch machines of railway systems.

The safety afforded by the locking of power operated track switches is based on the premise, that if the signals associated with a particular switch have assumed the stop position for a predetermined time, usually slightly in excess of the time required for a train to come to a stop from its maximum speed, it will be safe to operate the switch in that the train will either have come to a stop, will be occupying the detector locking circuit or will have passed entirely over the switch points. As a time measuring device it is convenient to use a thermal relay, but if such a thermal relay is used it is important that such relay shall have returned to its normal cool condition before it is again called upon to carry out its time measuring function, and in accordance with the present invention the thermal relay is proposed to be put into service upon placing a signal in the stop position, and this signal or any other associated signal cannot again be cleared until the thermal relay has returned to its normal cold condition.

Other objects, purposes and characteristic features of the present invention will in part be obvious from the accompanying drawing and will in part be pointed out hereinafter.

In describing the invention in detail reference will be made to the accompanying drawing, in which:—

Fig. 1 illustrates conventionally an embodiment of the invention as applied to a single switch machine for operating a track switch, which has associated therewith signals for governing traffic in either direction over either of two routes establishable by such track switch; and

Fig. 2 illustrates the signal control relay in its deenergized condition, illustrating the manner in which the contact segment may be locked in its abnormal condition by the back contact of the signal control relay.

Referring to Fig. 1 the track rails 1 of the railway system have been shown divided into insulating sections by insulating joints 2 to facilitate track circuiting, of which only the detector track circuit containing the detector

track relay T and the track battery 3 has been illustrated, this detector track circuit signifying the passage of a train over the switch points of track switch S. This track switch S may be operated by a suitable power operated switch machine SM, which in turn is controlled by the switch machine control relay WZ. The movement of traffic toward the switch points is governed by the main entering signal 8 and the take siding signal 8^d, and the movement of traffic into the single track section is governed by the main starting signal 7 and the dwarf starting signal 7^d. These signals 7, 7^d, 8 and 8^d are governed by the signal control relay SZ, and may clear only in the event that the switch machine SM assumes the proper position for the particular route over which traffic is governed by a particular signal, and providing of course that traffic conditions in advance is favorable as determined by a suitable signal system, such as an absolute-permissive-block signaling system, as conventionally shown by the home relays H^e and H^s. Associated with the signal control relay SZ is a thermal relay TR which thermal relay TR is mechanically co-ordinated with the back contact 10 of the signal control relay SZ through the medium of a sector 26. This thermal relay TR controls and is controlled by the signal relay SZ and in turn also controls the lock relay LR. These relays SZ and WZ are controlled from a central dispatcher's office DO through the levers WL and SL, respectively, all in a manner more clearly pointed out in connection with the operation of the system.

Operation

As shown in the drawing the signal control lever SL is now in its right-hand position, signifying east bound traffic, and maintains the signal relay SZ in its right hand energized position through the following circuit:—beginning at the terminal (+) of the central office battery, signal lever SL, wire 12, relay SZ, wire 13, thermal element 14 (this thermal element is one of the usual bimetallic type comprising two metals which have different temperature co-efficients of expansion welded together so that the unitary

structure bends in accordance with change in temperature, this element 14 bending upwardly in response to heating of the same), wires 15 and 16 back to the midpoint C of the central office battery.

- Attention is directed to the fact that the thermal element 14 is now assuming its normal cooled position in engagement with its back contact, and that this element will be 10 bent upwardly in response to the heating by its coil 17 surrounding the element 14. With the circuit just traced complete and energized the polar contact 18 will assume its right hand position and the neutral contact 10 will 15 assume its raised position, so that the following circuit for the signal 8 is closed:—beginning at the terminal (+) of a suitable way station battery, front contact 10 of the relay SZ, wire 20, polar contact 18 of the relay SZ, wire 21, front contact 24 of relay H⁸, switch machine contact 22 closed only when the switch machine assumes its main track position, wire 23, mechanism of the signal 8 to the other terminal (—) of said battery.
- 25 It is of course understood that it would be hazardous to permit the operator at the central office DO to move his signal 8 to the stop position and immediately thereafter operate the switch machine SM, this because an approaching train moving at high speed might arrive at the switch S before it had completed its stroke or might be caused to take the siding at high speed and be derailed. For this reason, it is proposed in accordance with the 30 present invention to require the lapse of a predetermined period of time after the signal 8, or any one of the other signals, has been operated to the stop position before the switch points may be operated.
- 40 Let us now assume that the operator wishes to move the switch machine SM to the take siding position. If he moves his switch machine lever WL to the dotted position, signifying the take siding position, no response 45 will take place for the circuit for the relay WZ is open at the front contact 25 of the lock relay LR. Let us, however, assume that the operator leaves his switch machine control lever WL in the dotted position and then 50 operates his signal lever SL to the intermediate stop position. This movement of the lever SL to the neutral stop position effects de-energization of the relay SZ and in turn effects opening of the energizing circuit for the 55 semaphore signal 8, this by dropping of the contact 10 of the relay SZ. With this contact 10 of the relay SZ released it will engage the upper segment 26¹ of the angle lever or sector 26, thereby closing the following 60 circuit for the coil 17 of the thermal relay TR:—beginning at the terminal (+) of the way station battery, back contact 10 of the relay SZ, sector 26¹ of the angle lever 26, wire 27, coil 17 of the thermal relay TR to

the other terminal (—) of the way station battery.

The closure of this circuit will of course heat the coil 17 and after the lapse of a pre-determined time, say one to four minutes, the 70 sector 26 will have been rotated in a right hand direction until the contact 10 drops from the segment 26¹ upon the segment 26², these segments being insulated from each other by insulation 26³. This new position 75 of contact 10 is shown in Fig. 2 of the drawing. Under this condition of the contact 10 the following circuit for the lock relay LR is completed:—beginning at the terminal (+), contact 10 of the relay SZ, sector 26², wire 28, winding of the lock relay L to the other terminal (—) of the way station battery.

The completion of this circuit will close the contact 25 of relay LR, and since the lever WL assumes its dotted position the switch 85 machine relay WZ will be energized through the following circuit:—beginning at the terminal (—) of the central office battery, lever WL in the dotted position, line wire 30, front contact 25 of the relay LR, wire 31, winding 90 of the relay WZ, wires 32 and 16, back to the midpoint of the central office battery.

The completion of this circuit will of course 95 operate the polar contact 35 of the relay WZ to its left hand position and will effect closure of the neutral contact 36 of this relay WZ, so that the switch machine SM may be operated to its take siding position through the following circuit:—beginning at the terminal (+) of the way station battery, front contact 37 of the track relay T, wire 38, neutral contact 36 of the relay WZ, polar contact 35 of the relay WZ assuming its dotted position, reverse wire R through the motor 100 of the switch machine to the other terminal (—) of the way station battery. The completion of this circuit will of course operate the switch machine SM to its take-siding position upon the consummation of which the circuit will be broken by suitable means 110 within the switch machine (not shown).

Let us now assume that the operator wishes to clear the starting signal 7^a, that is, wishes to set up west bound traffic off of the side track of the passing siding PS. To accomplish this he will move his signal lever SL to its left hand dotted position, but the signal relay SZ cannot be energized until the thermal relay TR has again cooled sufficiently to cause the thermal blade 14 to engage its co-operating back contact, after which the signal relay SZ will be energized to its left hand dotted position and complete the following circuit for the signal 7^a:—beginning at the 120 terminal (+), front contact 10 of the relay SZ, wire 20, polar contact 18 assuming its left-hand position, wire 40, front contact 39 of the relay H⁷, the switch machine contact 41 assuming its take-siding position, wire 42, 130

mechanism of the signal 7^d to the other terminal (—) of the way station battery. The closure of this circuit will of course clear the signal 7^d and allow the passage of a west bound train off of the side track of passing siding PS.

Similarly, the signals 7 and 8^d may be cleared if the switch S assumes the proper position, this through the medium of wires 43 and 44 in a manner readily understood from the drawing.

It is thus noted that the track switch S cannot be operated until a predetermined period of time has elapsed after the signals 7, 7^d, 8 and 8^d all assume the stop position, and that after operation of the switch machine and its associated track switch S these signals, or any one of them cannot be cleared until the thermal relay TR has returned to its normal cooled position. It should also be noted that the switch machine SM cannot be operated unless the detector track relay TR is energized, this by reason of the fact that the front contact 37 of the track relay T included in the operating circuits of the switch machine SM. The switch machine may of course be returned to its normal position by the closure of its normal operating circuit including the normal wire N providing, of course, that conditions are otherwise proper.

Applicant has thus shown and described one rather specific embodiment of the present invention, but it is desired to be understood that the particular embodiment selected has not been selected for the purpose of showing the scope of the invention or the exact construction preferably employed in practicing the invention, but has been selected for the purpose of facilitating a description of the underlying principles of the invention, and the manner in which these principles may be employed in practicing the same; and it is further desired to be understood that certain modifications and additions may be made to the invention as illustrated to adapt it to the particular problems encountered in practicing the same, all without departing from the spirit or scope of the invention or the idea of means underlying the same, except as demanded by the scope of the following claims.

What I claim as new is:—

1. In combination, a track switch of a railway system, a switch machine for operating said switch, a signal associated with said switch for governing movement of traffic over said switch, and a relay having a contact which if in its attracted position closes a circuit for clearing said signal and when its control circuit is open and said contact assumes its retracted position it closes a circuit for controlling said switch machine, whereby said switch machine cannot be operated unless said signal is at stop.

2. In combination, a track switch of a railway system, a switch machine for operating said switch, a plurality of signals associated with said switch for governing movement of traffic over said switch, and a relay having a contact which if its attracted position closes a circuit for clearing any one of said signals and when its control circuit is open and said contact assumes its retracted position it closes a circuit for controlling said switch machine, whereby said switch machine cannot be operated unless all of said signals are at stop.

3. In combination, a track switch of a railway system, a switch machine for operating said switch, a signal associated with said switch for governing movement of traffic over said switch, a relay having a contact which if in its attracted position closes a circuit for clearing said signal and when in its retracted position closes a circuit for controlling said switch machine, and timing means for delaying the movement of said contact to said retracted position, whereby said switch machine cannot be operated until after a lapse of time after said signal has been put to stop.

4. In combination, a track switch of a railway system, a switch machine for operating said switch, a plurality of signals associated with said switch for governing movement of traffic over said switch, a relay having a contact which if in its attracted position closes a circuit for clearing any one of said signals and when in its retracted position closes a circuit for controlling said switch machine, and timing means for delaying the movement of said contact to said retracted position, whereby said switch machine cannot be operated until said signals have been at stop for a predetermined period of time.

5. The combination with a track switch of a railway system, of a switch machine for operating said switch, a signal associated with said switch for governing movement of traffic over said switch, a lock relay which if deenergized prevents operation of said switch, a control relay for controlling said signal to permit clearing of said signal only when said control relay is energized, a time element device rendered active to energize said lock relay a predetermined time after being energized, a circuit for said time element device including a back contact of said control relay, and a circuit for said control relay including a normally closed contact of said time element device.

6. The combination with a track switch of a railway system, of a switch machine for operating said switch, a signal associated with said switch for governing movement of traffic over said switch, a lock relay which if deenergized prevents operation of said switch, a control relay for controlling said signal to permit clearing of said signal only when said control relay is energized, a time element device for normally preventing a

back contact of said control relay from assuming its retracted position but which upon being energized for a predetermined period of time will allow it to assume such retracted position and energized only upon deenergization of said control relay, and a circuit for said lock relay including said back contact of said control relay.

7. The combination with a track switch of a railway system, of a switch machine for operating said switch, a signal associated with said switch for governing movement of traffic over said switch, a lock relay which if deenergized prevents operation of said switch, a control relay for controlling said signal to permit clearing of said signal only when said control relay is energized, a time element device for normally preventing a back contact of said control relay from assuming its retracted position but which upon being energized for a predetermined period of time will allow it to assume such retracted position and energized only upon deenergization of said control relay, a circuit for said lock relay including said back contact of said control relay, and means for deenergizing said time element device such predetermined period of time after being energized.

8. The combination with a track switch of a railway system, of a switch machine for operating said switch, a signal associated with said switch for governing movement of traffic over said switch, a lock relay which if deenergized prevents operation of said switch, a control for controlling said signal to permit clearing of said signal only when said control relay is energized, a latch for preventing a contact of said control relay assuming its retracted position, a time element device for operating said latch to its active non-latching position, a circuit for said time element device closed when said control relay is deenergized and said latch assumes its latching position, and a circuit for said lock relay closed only when the contact of said control relay assumes its retracted position.

9. In combination, a track switch, a switch machine for operating said track switch, a signal for governing movement of traffic over said track switch, a signal relay which if energized permits clearing of said signal, a switch machine relay for controlling said switch machine, two levers, two line circuits, one lever for controlling the energization of said signal relay over one line circuit and the other lever for controlling the energization of said switch machine relay over the other line circuit, and a contact in the control circuit of said switch machine relay closed only if said signal control relay is deenergized.

10. In combination, a track switch, a switch machine for operating said track switch, a signal for governing movement of traffic over said track switch, a signal relay which if energized permits clearing of said signal, a

switch machine relay for controlling said switch machine, two levers, one for energizing said signal relay and the other for energizing said switch machine relay, and a contact in the control circuit of said switch machine relay closed only if said signal control relay is deenergized and has been deenergized for a predetermined period of time.

11. The combination with a track switch of a railway system, of a switch machine for operating said switch, a signal associated with said switch for governing movement of traffic over said switch, a lock relay which if deenergized prevents operation of said switch, a control relay for controlling said signal to permit clearing of said signal only when said control relay is energized, a circuit for said lock relay closed only if said signal control relay is deenergized and a thermal relay assumes its active heated condition, and a circuit for said signal control relay closed only when said thermal relay assumes its normal inactive condition, whereby it is assured that said thermal relay has been sufficiently cooled before it is again called upon to function.

12. In combination, a track switch of a railway system, a switch machine for operating said switch, a signal associated with said switch for governing movement of traffic over said switch, a thermal relay having a normal cool condition and an active heated condition, a circuit which must be closed to effect operation of said switch and closed only if said thermal relay has been caused to assume its heated condition, and a circuit for said signal which can be closed only if said thermal relay assumes its normal cool condition.

In testimony whereof I affix my signature. 105
